UNITED STATES PATENT OFFICE.

JOHN SOLTER, OF BALTIMORE, MARYLAND, ASSIGNOR TO GEO. V. KEEN
AND JAMES S. HAGERTY, OF SAME PLACE.

SLOP JAR OR BUCKET.

SPECIFICATION forming part of Letters Patent No. 226,562, dated April 13, 1880.

Application filed March 5, 1880. (No model.)

To all whom it may concern:

Be it known that I, JOHN SOLTER, of the city of Baltimore, and State of Maryland, have invented certain Improvements in Slop Jars or Buckets, of which the following is a full, clear, and exact description, reference being had to the accompanying drawings, forming a part hereof.

The invention consists in providing the slop jar or bucket with an upper extension which, by its construction, prevents the splashing over of water when poured upon the ordinary top of the jar.

In the drawings, Figure I is a vertical section of the invention. Fig. II is a top view of the same. Fig. III is a vertical section showing a modified construction. Fig. IV is a top view of the same.

Similar letters of reference indicate similar parts in all the views.

A is the body of the slop jar or bucket, having the ordinary removable plate-top a. In Figs. I and II the said top rests on the top of the flange at the mouth of the jar, while in Figs. III and IV the said top is below the upper part of the enlargement a', and rests upon the ledge a''.

In Figs. I and II the top a is provided with an upper extension, B, consisting of the flaring projection b, surmounted by the funnel c. 30 Waste-water poured into the funnel c will not have a tendency to splash over its upper edge, but will be deflected in a downward direction and caught by the flaring projection b, which prevents its return to the funnel. The water 35 then finds its way through the center of the top a to the jar.

In Figs. III and IV the top a rests within the enlarged mouth a' of the jar, the depth of the molding affording the necessary space for 40 the water, which, poured therein, will be caught by the flaring projection b, with the same result as above described.

I claim as my invention—

A slop jar or bucket having the ordinary 45 removable plate-top a, and enlarged mouth a', combined with the upper extension, B, the said plate-top being below the base of said extension, substantially as specified.

JOHN SOLTER.
